TELESCOPE RETICULE ADJUSTMENT

John Unertl, Pittsburgh, Pa.

Application March 7, 1939, Serial No. 260,365

4 Claims. (CL. 33—50)

My invention relates to telescopes and more particularly to an improved means for adjustably mounting the reticule or cross-hair support of a telescope used as a sighting device for firearms, 5 that is, a telescopic gun-sight.

In the past, it has been difficult to so design a telescopic gun-sight that it is possible to obtain the required fine and consistent adjustment of the reticule to correct for variations in wind- 10 age and elevation, and, at the same time, to provide a rugged structure capable of withstanding the shocks and vibrations incident to the use of high-speed and high-velocity cartridges in guns with which telescopic sights are usually associated. 15 Commonly the reticule and its support are adjustably mounted on a system of dove-tail or mortised joints involving substantial mechanical complication, or, if simplification is attempted, a resilient support is proposed which introduces 20 variable stresses under different adjustments and usually is not adequate to take care of recoil shocks to which the scope is subjected in ordinary service. In many structures heretofore proposed, complication has been of doubtful benefit 25 and not justified by the expense involved.

It is an object of the present invention, therefore, to provide a reticule mounting for a gun-sight telescope which is substantially simpler than those of commensurate ruggedness used heretofore, and which is substantially more accurate and reproducible in adjustment than in 30 adjustable means heretofore obtainable.

Other objects will be apparent from the following description and the appended claims, with 35 reference to the accompanying drawing wherein:

Figure 1 is a view in vertical section of a telescope embodying the invention;

Fig. 2 is an enlarged view in vertical section of a portion of the structure shown in Fig. 1, and corresponds to a view taken on the line II—II 40 of Fig. 3;

Fig. 3 is a view taken on the III—III of Fig. 2;

Fig. 4 is a view in section of an element of the structure shown in Figs. 2 and 3; and

Fig. 5 is a view in section of a modification of the structure shown in the preceding figures.

Referring to Fig. 1, the invention is applicable to a telescope having a tubular body 2, an objective lens 4, an inverting lens 5 and an eye piece 6, the latter carrying with it a lens 8 adjustably mounted for focusing in any desired manner.

As is usual in scopes of this character, a cross-hair or the equivalent, is used to center on the target, and in the present invention, the cross-hair or reticule 10 (Fig. 3) is mounted on or in

a supporting frame 12 in any desired manner. For varying wind conditions, as well as for altitude conditions imposed by the desired trajectory, it is necessary that the cross-hair or reticule be capable of adjustment both horizontally and vertically with respect to the axis of the scope, 5 and this is accomplished by the improved construction now to be described.

As shown in the drawing, the reticule support 12 is to be disposed in the focal plane of the objective lens, but obviously it may be placed in the focal plane of the eye-piece if desired.

The mounting of the reticule support is accomplished by a tubular member 16 disposed within the body 2 of the scope and suitably secured to 15 the scope as by screws 17. The member 16 is provided with a circular recess into which is tightly fitted one end of a helical spring 20 extending axially of the scope body 2 and has secured at its free end the reticule support or frame 20 12. Preferably the spring 20 is of such section 25 and resiliency that the reticule support is readily moved laterally by the adjusting knobs 25 acting in conjunction with members 32, but the spring is quite stiff longitudinally of the scope. This permits relatively free lateral adjustment without the reticule support without tilting and sufficient resiliency longitudinally to take care of the recoil shock of the gun.

Preferably the spring 20 may be of flattened 30 material, rather closely wound as shown in Figs. 1 to 4, but it may in some cases be of rounded cross-section as shown in Fig. 5.

Referring further to Figs. 1 to 4, the horizontal and vertical adjustment of the reticule support is accomplished by means of threaded members 22 and 24 screwed through the side wall of a supporting member 26 and the side wall of the scope body 2 into engagement with the reticule support. Each threaded member 22 is 40 provided with a knurled head 25 and a large opposite end for engaging a flattened surface on the reticule support. The threaded members 22 and 24 are spaced 90° from each other radially 45 of the axis of the scope and flattened surfaces 45 on the reticule frame or support are provided to confront the ends of the members.

It is intended that the area of the bearing surface between the ends of the adjusting members 22 and 24 and the flattened surfaces on the 50 reticule support be as large as practicable in order to maintain the reticule perpendicular to the axis of the scope as it is moved laterally thereof when adjustments are made.

In order to stabilize the reticule support, a 55

compression spring 30 having a housing 31 secured to the scope body and a bearing member 32, is disposed to exert a force on the support 12. It will be noted that the engagement of the 5 threaded members 22 and 24 are spaced 90° from each other, and the spring 30 is spaced at approximately 135° radially of the axis of the scope from each of them. The system is therefore properly stabilized. The spring 20 is of sufficient 10 lateral resiliency to make the reticule support follow the adjusted movement of the adjusting members 22 and 24, without being so stiff that the reticule support will tend to tilt when adjustments are made.

15 In other words, assuming that the adjusting member 22 is screwed down, the support 12 must move vertically across the face of the threaded member 24 against the force of spring 30. The same is true for a horizontal adjustment, and 20 naturally follows from the three-point support of the reticule and the flat confronting surfaces of the members.

It is customary in devices of this character, 25 to provide a "click" device to measure the extent of the lateral and vertical adjustments. To that end, it is proposed to mount a resilient spring 35 (Fig. 3) in the supporting member 26 so that the free ends thereof, disposed in recesses adjacent to the knurled heads of the threaded 30 members 22 and 24, engage such heads to resiliently oppose the rotation thereof. It is understood of course that the heads of the threaded members and the ends of the "click" device are 35 enclosed or covered by a suitable threaded cap 38.

The structure thus far described provides a desired mounting for the reticule of a gun-sight telescope, in that it insures that the reticule support is maintained vertical to the axis of the 40 scope by reason of the three-point bearing surfaces of maximum dimension. However, in order to take care of extreme conditions, the modification shown in Fig. 5 is suggested. Here the helical spring 40 is round in cross section and the 45 reticule frame or support 42 is provided with a flattened or plane front face disposed to slide over the confronting face of a recoil-resisting member 44 fixed within the scope, as by screws 46.

50 By the construction described, an unusually cheap and efficient means has been provided for the reticule adjustment of a gun-sight and since modifications in the structure disclosed may readily present themselves, it is intended that the invention be limited only by the scope of the appended claims.

I claim as my invention:

1. In a telescope comprising a tubular body and a reticule support therein, means for adjustably mounting said reticule support in operative position comprising a helical spring within said body and extending axially thereof, means for securing one end of said spring with respect to the inner wall of the body with the line of sight of the telescope passing through the spring, 60

means for securing said reticule support to the free end of said spring, and means operable from outside said body for adjusting the position of said reticule support with respect to the axis of said body. 5

2. In a telescope comprising a tubular body and a reticule support therein, means for adjustably mounting said reticule support in operative position comprising a helical spring within said body extending axially thereof and substantially 10 coaxially therewith, means for securing one end of said spring with respect to the inner wall of the body, means for securing said reticule support to the free end of said spring, said spring being of flattened material of substantially greater 15 width than thickness, and means operable from outside of said body for engaging the reticule support to adjust the position thereof with respect to the axis of the body. 15

3. In a telescope comprising a tubular body 20 and a reticule support therein, means for adjustably mounting said reticule support in operative position comprising a helical spring within said body extending axially thereof and substantially 25 coaxially therewith, means for securing one end of said spring with respect to the inner wall of the body, means for securing said reticule support to the free end of said spring, and means operable from outside said body for adjusting 30 the position of said reticule support with respect to the axis of said body including a pair of threaded members extending through the body wall and displaced 90° apart radially of the body, a pair of flattened surfaces on said reticule support at right angles to each other to be engaged 35 by the inner ends of said threaded members, and resilient means for biasing said reticule support into engagement with said inner ends of the threaded members.

4. In a telescope comprising a tubular body, 40 and a reticule support therein, means for adjustably mounting said reticule support in operative position comprising a helical spring within said body and extending axially thereof, means for securing one end of said spring with 45 respect to the inner wall of the body, means for securing said reticule support to the free end of said spring the line of sight passing axially through said spring, and means operable from outside said body for adjusting the position of said reticule support with respect to the axis of said body including a pair of threaded members 50 extending through the body wall and displaced 90° apart radially of the body, a pair of flattened surfaces on said reticule support at right angles to each other to be engaged by the inner ends of said threaded members, resilient means for biasing said reticule support into engagement with said inner ends of the threaded members, and means secured within said body for guiding 60 said reticule support in a plane at right angles to the axis of the body upon actuation of said threaded members. 55

JOHN UNERTL.
